UNITED STATES PATENT OFFICE

FRED M. ROSENZWEIG, OF NIAGARA FALLS, NEW YORK, ASSIGNOR TO THE REGAN SAFETY DEVICES COMPANY, INC., OF NEW YORK, N. Y., A CORPORATION OF NEW YORK

TRAIN-CONTROL SYSTEM

Application filed March 13, 1924. Serial No. 699,138.

This invention relates to a train control system, and more particularly to a train control system in which a train or vehicle is automatically controlled from the roadside 5 to produce restrictive movements of the vehicle, and in which such restricted movements may be modified by manual intervention of the engineman to permit the vehicle to proceed under given speed limitations.

10 A prime desideratum of my present invention comprehends the provision of a train control system in which after a given restriction is imposed on the movement of the vehicle in response to a "non-clear" roadside 15 condition, the restriction may be modified by a manual intervention of the engineman only when the vehicle has been reduced to a speed at or below a relatively low limit which is less restrictive than the given restriction,

20 the manual control being such as to then permit the acceleration of the speed of the vehicle to a second and relatively higher speed limit.

A correlative object of the invention centers about the provision of a train control system of this character in which the manual control is so designed as not to interfere with the automatic control of the vehicle from the roadside, the manual modification of the automatically imposed restriction being such as 25 to permit automatic control from the roadside when the next roadside control station is reached.

In the train control system of my invention, for controlling the movement of the vehicle there is provided a vehicle carried device which is operated to produce vehicle "proceed" and "stop" operations by means of cooperating vehicle carried and roadside 35 mechanism. The vehicle carried and roadside mechanism operate in response to changing roadside conditions for impressing upon the vehicle the "proceed" and "stop" operations, the change in vehicle operation being effective during the period in which the ve-

hicle carried mechanism moves over the controlling roadside mechanism. When the system is of the ramp or contact type, this period of cooperation may be substantial and may extend over a running distance of one hundred feet. It is undesirable, however, to produce a complete "stop" of the vehicle when the shoe is in engagement with the ramp; and to obviate this objection, it is a further object of my invention to provide means for modifying an automatic "stop" operation so as to permit the vehicle to proceed during the period of engagement between a shoe and a ramp, and in the preferred embodiment of the invention to permit such "proceed" movement under a speed limitation.

To the accomplishment of the foregoing and such other objects as may hereinafter appear, my invention consists in the elements and their relation one to the other, as hereinafter particularly described and sought to be defined in the claims; reference being had to the accompanying drawing which show a preferred embodiment of my invention, and in which:

The figure is a wiring diagrammatic view showing the vehicle carried apparatus and circuits and part of the roadside apparatus cooperating therewith.

Referring now more in detail to the drawing, for directly controlling the movement of the vehicle there is provided an electrically operated device for controlling the operation of the air brake system, the said device being under the control of cooperating vehicle and roadside mechanism and being operated thereby in accordance with roadside conditions. The electrically operated device comprises in the preferred embodiment of the invention an electromagnet 10 which controls the operation of a combined reservoir and brake valve 11 preferably of the type described and claimed in the patent to A. B. Kendall No. 1,474,836 of Nov. 20, 1923, the said reservoir and brake valve func-

tioning upon the deenergization of the electromagnet 10 for cutting off the supply of air from the main reservoir of the air brake system to the engineman's brake valve and for opening the train pipe to exhaust, the said electromagnet 10 being normally energized to hold open the communication between the main reservoir and the engineman's brake valve and to close the train pipe to exhaust.

10 For controlling the operation of the electromagnet device 10, there are provided train carried circuits which are selectively operated in response to changing roadside conditions, and in the exemplified system shown in the 15 drawings, the train carried circuits are constructed and arranged to be operated in response to "clear", "caution" and "danger" roadside conditions for producing corresponding "proceed", "proceed at restrictive 20 speed" and "stop" operations of the electromagnet 10.

For operating the electromagnet 10 in response to "clear" roadside conditions, the same is energized by the circuit comprising 25 the vehicle carried battery 12, resistance 13, conductor 14, electromagnet 10, conductor 15, a make and break indicating means 16 which normally occupies the full-line position *a* shown in the drawing and which is 30 movable in response to "caution" roadside conditions for assuming the inclined dotted-line position *b*, and in response to "danger" conditions for assuming the vertical dotted-line position *c*, conductor 17 running to a 35 high speed contact *H* closed by a speed controller 18 when the vehicle is traveling at or below a high speed limit, common contact *C*, conductor 19, and conductor 20 back to the battery 12. With the provision of this circuit, it will be manifest that with the indicating means 16 in the position *a* the train will be permitted to proceed provided a predetermined high speed limit is not exceeded, and that if such speed limit is exceeded, the 45 air brake mechanism will be operated to reduce the speed of movement of the vehicle to or below the said predetermined high speed. While in the embodiment shown I prefer to include a high speed control of a vehicle, it will be understood that the electromagnet 10 may be directly controlled by the described circuit exclusive of the speed controller.

For operating the electromagnet 10 in response to "caution" roadside conditions, the same is controlled by a "caution" circuit comprising the battery 12, resistance 13, conductor 14, electromagnet 10, conductor 15, indicating make and break means 16 in position *b*, conductor 21, conductor 22, medium speed contact *M* of the speed controller 18 closed by the speed controller when the train reaches a medium speed, common contact *C*, conductors 19 and 20, to battery 12. Thus 60 when the indication make and break means

16 is operated under "caution" conditions to the positon *b*, the electromagnet 10 will be placed under the control of said make and break means and a medium speed limit of the vehicle.

It will be apparent from the foregoing that when the indication means 16 is moved to the "neutral" or dotted line position *c*, both the "clear" and "caution" circuits controlling the electromagnet 10 will be open and the said electromagnet will be deenergized to bring the vehicle to a stop.

For operating the make and break indicating means 16, I provide cooperative vehicle carried and roadside mechanism which in the exemplified embodiment shown in the drawings comprises a vehicle carried shoe mechanism generally designated as *S*, arranged to engage and ride over a plurality of ramps *R* (one of which is shown in the drawing), the said ramps being located at spaced controlling stations along the roadside adjacent to the roadbed and rails 23, the movement of the shoe over a ramp being effective for operating an indication selector generally designated as *I* selectively in accordance with roadside conditions.

For producing the desired operations of the indication means *I*, the roadside ramps *R* are controlled by roadside circuit mechanism of the type disclosed in the patent of A. G. Shaver, 1,505,062 of Aug. 12, 1924, the control being such that under "clear" roadside conditions the ramp *R* is energized with a current of a given polarity and under "caution" roadside conditions said ramp is energized with current of a reverse or opposite polarity, and under "danger" roadside conditions the ramp is deenergized.

The indication means *I* may be of the type disclosed in the Letters Patent of Theodore Bodde, Patent No. 1,527,465 of Feb. 24, 1925, and may be diagrammatically described as comprising a field magnet 24, an armature rotor 25 movable into the positions *a'*, *b'*, and *c'* when the field coil 24 is energized respectively with current of a given polarity, of a polarity opposite to said given polarity, and is deenergized, the said indication selector further including a clutch or holding device consisting of a holding magnet 26 provided with the oppositely arranged poles 27, 28 arranged for cooperation with an armature 29 fixed to and movable with the rotor 25. When the vehicle is moving between control stations or ramps *R* under "clear" roadside conditions, the parts of the indication selector occupy the position as shown in full lines in the drawing, the holding magnet 26 being energized to hold the armature 29 and rotor 25 in the position indicated, by means of the circuit comprising the battery 12, resistance 13, conductor 30, contacts 31 and 32 bridged by the conducting piece 34 fixed to for movement with the shoe *S*, conductor 35, coil of

holding magnet 26, conductor 36, a make and break means 16' movable together with the make and break means 16 and operated by the movements of the indication rotor 25 to positions a^2 , b^2 and c^2 , the described circuit being completed by the conductor 20.

When the shoe S rides a ramp R, the circuit to the holding magnet 26 is broken at the contact 32 and the rotor 25 is free to move to the position c' , for actuating make and break means 16 and 16' to the respective positions c and c^2 . The further operation of the indication means I is determined by the energization of the ramp R which energizes the vehicle carried partial circuit controlling the field coil 24, the said partial circuit comprising the shoe S, conductor 37, coil 24, conductor 38 connected to ground at the framework of the vehicle 39.

It will be apparent from the foregoing that under "clear" roadside conditions the partial circuit which controls the field core 24 is energized so as to move the operated parts of the indication means I and the make and break means 16 and 16' to the "clear" indicating position shown in full lines in the drawings, and that under "caution" roadside conditions the said partial circuit is energized to move the operated parts of the indication means to the "caution" indicating position, and that further under "danger" roadside conditions the said partial circuit is deenergized to permit the movement of the operated parts of the indication means I to the "neutral" and vehicle "stop producing" positions.

As heretofore mentioned, a prime desideratum of my present invention comprehends the provision of a train control system in which an automatically imposed restriction such as an automatic "stop" operation may be modified by the engineman if he is alert to permit the vehicle to proceed provided the speed of the vehicle has first been reduced to a predetermined low limit, after which the speed of the vehicle may then be increased to a predetermined higher limit such as a medium speed.

To accomplish this object of the invention, I provide manually controllable mechanism for operating the indication means I after the operated parts thereof have been moved to the "neutral" or "stop" producing position, for placing the same under the control of a medium speed restriction, said mechanism being operably effective, however, only after the vehicle has been reduced to the desired low speed limit. In manually operating the indication means I, it is desirable to prevent any interference of the automatic control of the said indication means by the cooperative vehicle carried and roadside mechanism, and to accomplish this, it is a further object of the invention to manually control the operation of the indicating means while permitting the automatic operation of the same by the road-

side mechanism when the next control station is reached.

To modify the "stop" operation and permit the acceleration after the reduction of speed, I provide circuit mechanism for operating the field coil 24 of the indication means I, the said circuit mechanism comprising the battery 12, resistance 13, conductor 14, conductor 40, normally open contact 41, conductor 42, field coil 24, conductor 37, conductor 43, normally open contact 44, a conductor 45, a low speed contact L normally open and closed by the speed controller 18 when the speed of the vehicle has been reduced to a low limit, common contact C and conductors 19 and 20. The contacts 41 and 44 which are normally open are adapted to be closed manually by the engineman by operating a circuit controlling mechanism generally designated as 46 of the type disclosed in the application of A. G. Shaver, Ser. No. 634,053 of April 23, 1923, the circuit controlling mechanism comprising generally a receptacle push button device 47 holding a fluid in which is seated a piston stem 48 which may be connected to the contacts 41 and 44, the construction being such that upon operation of the push button receptacle 47 the fluid therein transmits the operating impulse to the stem 48 to close the contacts 41 and 44 and to permit the stem and contacts to move to the descended position shown in the drawing regardless of the further operation of the push button receptacle 47. This mechanism is provided so that the circuit controlled thereby can be closed only momentarily and cannot be held closed by holding the push button in an elevated position.

By manually operating the circuit controlling mechanism 46, the coil 24 of the indication means I is energized by current having such a direction that the operated parts of the indication means I are moved to the "caution" indicating positions, with the make and break means 16 and 16' moved to the positions b and b^2 . For a further explanation of the relative flow of currents to accomplish the desired results, I may refer to the patent of A. G. Shaver No. 1,505,062 of Aug. 12, 1924. Although the operation of the indication means I is but momentary, it will be apparent that the movement of the make and break means 16 and 16' to the positions b and b^2 closes a circuit to the holding magnet 26 for maintaining the rotor 25 in the "caution" indicating position, the said circuit comprising battery 12, resistance 13, conductor 30, the contacts of shoe mechanism S, conductor 35, holding magnet 26, conductor 36, make and break means 16' in position b^2 , conductor 49, conductor 22, medium speed contact M, speed controller 18, common contact C, and conductors 19 and 20.

It will be seen that with the provision of the circuit mechanism described, the indication means I is operated only when the ve-

hicle has been reduced to the low speed limit, and that such operation places the indication means I under the control of the medium speed contact of the speed controller so that the speed of the vehicle may be accelerated from the low speed to a medium running speed; and it will be further seen that the indication means is so operated that the holding magnet 26 thereof is placed under the control of the speed controller 18 and the shoe mechanism S, so that when the shoe reaches the next control ramp the elevation of said shoe will break the holding circuit to again automatically operate the indication means I in accordance with roadside conditions.

As has heretofore been stated, to prevent the stopping of the vehicle with the shoe in engagement with the ramp, another object of the invention centers about the provision of means for modifying the "stop" and permitting the vehicle to proceed during the period of engagement between a shoe and a ramp. To accomplish this object of the invention, I provide means for automatically operating the electromagnet 10 to maintain the same energized during the time that a shoe engages a ramp, and in the preferred embodiment of the invention the said electromagnet 10 is during this time placed under the control of a low speed restriction so that the vehicle can only proceed at or below a low speed limit if a deenergized ramp is being engaged. The said means for operating the electromagnet 10 comprises battery 12, resistance 13, conductor 14, electromagnet 10, conductor 15, conductor 50 connected to a contact 51 normally open when the shoe is in descended position to be bridged by a conducting piece 52 when the shoe is elevated by engagement with the ramp, the circuit being then closed by the contact 53, conductor 54, conductor 45, low speed contact L, speed controller 18, common contact C, and conductors 19 and 20. When this circuit is closed by the elevation of the shoe, the magnet 10 is energized to permit the vehicle to proceed at or below the low speed limit determined by the low speed contact L, and this circuit is again opened when the shoe leaves the ramp. On leaving the ramp the release means 47 may be operated as before described to permit the acceleration of the train to the medium speed.

While I have shown my invention in the preferred form, it will be obvious that many changes and modifications may be made in the structure disclosed without departing from the spirit of the invention, defined in the following claims.

I claim:

1. In a speed control system for vehicles, vehicle carried mechanism comprising a valve magnet for controlling the movement of the vehicle, circuit means operable in response to a "non-clear" roadside condition for operating the said magnet to impose a

"stop" condition on the movement of the vehicle, and manually controllable circuit mechanism operably effective only when the vehicle is moving at or below a relatively low speed limit for operating the said magnet to impose a second, relatively higher and fixed speed limit on the vehicle.

2. In a speed control system for vehicles, vehicle carried mechanism comprising a device for controlling the movement of the vehicle, an indication means for controlling the operation of said device, vehicle carried and roadside instrumentalities operated in response to roadside conditions for operating the said indication means to produce in the said device either a vehicle "proceed" or a vehicle restrictive operation, a speed controller, and manually controllable mechanism operable after a given restrictive operation is produced in said device in response to a "non-clear" roadside condition and operable only when the vehicle is moving at or below a relatively low speed limit which is less restrictive than the said given restriction for operating the indication means and for placing the same under the control of the speed controller and the said instrumentalities to impose a fixed speed limit on the vehicle higher than said relatively low speed limit and to permit the said indication means to be operated by the said instrumentalities in response to further roadside conditions.

3. In a speed control system for vehicles, vehicle carried mechanism comprising a device for controlling the movement of the vehicle, a three-position indication means for controlling the operation of said device, instrumentalities adapted to be operated by roadside mechanism in response to roadside conditions for operating the said indication means in any of three ways to produce in the said device either a vehicle "proceed," "proceed at a fixed medium speed" or a "stop" operation, a speed controller, and manually controllable mechanism connected to said speed controller and operable after a "stop" operation is produced in said device in response to a "danger" roadside condition and operable only when the vehicle is moving at or below a relatively low speed limit for operating the indication means and for placing the same under the control of the speed controller and the said instrumentalities to impose the fixed medium speed limit on the vehicle and to permit the said indication means to be operated by the said instrumentalities in response to further roadside conditions.

4. In a speed control system for vehicles, vehicle carried mechanism comprising a device for controlling the movement of the vehicle, vehicle carried and roadside means operable in response to "clear", "caution" and "danger" roadside conditions for operating the said device to produce respectively "pro-

ceed", "proceed under a speed restriction" and "stop" effects on the movement of the vehicle, and manually controlled mechanism operably effective when a "stop" effect is produced and only when the vehicle is moving at or below a relatively low speed for operating the said device to impose a second and relatively higher speed limit on the vehicle.

5. In a speed control system for vehicles, vehicle carried mechanism comprising a device for controlling the movement of the vehicle, circuit mechanism including a three-position indication means for operating the said device in response to "clear", "caution" and "danger" roadside conditions for producing corresponding "proceed", "proceed at restricted speed" and "retard" effects on the vehicle, and manually controllable mechanism operable after a "retard" effect is produced and only when the vehicle is moving at or below a relatively low speed limit for operating the said indication means to impose a second and fixed speed limit on the vehicle higher than said relatively low speed limit.

6. In a speed control system for vehicles, vehicle carried mechanism comprising a device for controlling the movement of the vehicle, a speed controller, mechanism including an indication means operable in response to "clear" roadside conditions for producing a "proceed" operation of said device and operable in response to "danger" roadside conditions for placing the said device under the control of said speed controller to impose a medium speed limit on the vehicle and operable further in response to "danger" roadside conditions for producing a "stop" operation of said device; and manually controllable mechanism operable after a "stop" operation of said device is produced and only when the vehicle is moving at or below a relatively low speed for operating the said indication means to again place the same under the control of the said speed controller to impose the medium speed limit on the vehicle.

7. In a vehicle control system, a vehicle carried device operable for controlling the movement of the vehicle, roadside mechanism located at a control station on the roadside, vehicle carried mechanism cooperating with the roadside mechanism for automatically operating the said device, and speed-controlled means automatically conditioned for operation by the coaction of said roadside and vehicle carried mechanism for operating the device only during the period of coaction between the roadside and vehicle carried mechanism to permit the vehicle to move beyond the control station under a restricted speed.

8. In a vehicle control system, a vehicle carried device operable for producing a vehicle "proceed" and a vehicle "speed restrictive" effect, roadside mechanism located at a control station on the roadside, vehicle car-

ried mechanism cooperating with the roadside mechanism for automatically operating the said device, and speed controlled means automatically conditioned for operation by the coaction of said roadside and vehicle carried mechanism for operating the device only during the period of cooperation between the roadside and vehicle carried mechanism to permit the vehicle to move under a speed limit beyond the control station when a restrictive operation of said device is produced.

9. In a vehicle control system, a vehicle carried device operable for controlling the movement of the vehicle, roadside ramps located at spaced controlling stations along the roadside, vehicle carried mechanism including a shoe movable over and in engagement with the ramps for operating the said device, the said device being operated by movement of the shoe under a "non-clear" roadside condition to produce a speed restrictive effect on the vehicle, and speed controlled means for automatically operating the device by and only during the engagement between the shoe and the ramp to permit the vehicle to move sufficiently to disengage the shoe from the ramp.

10. In a vehicle control system, a vehicle carried device operable for producing vehicle "proceed" and "stop" effects, roadside mechanism located at a control station on the roadside, vehicle carried mechanism cooperating with the roadside mechanism for automatically operating the said device, and speed controlled means for operating the device when the same is operated to produce a "stop" effect to permit the vehicle to move beyond the control station at or below a low speed limit, and means for automatically controlling the co-operation between said speed controlled means and said device during the period of cooperation between the roadside and vehicle carried mechanism.

11. In a vehicle control system, a vehicle carried device and circuit means operable for producing vehicle "proceed" and "stop" effects, roadside ramps located at spaced controlling stations along the roadside, vehicle carried mechanism including a shoe movable over the ramps for operating the said device, movement of the shoe over a ramp being effective for opening circuit connections to said device irrespective of the speed of the vehicle, and means operable by movement of the shoe on a ramp for closing circuit connections to said device and for placing the said device under the control of the speed of the vehicle to permit the vehicle to move beyond the control station at a restricted speed.

12. In a vehicle control system, a vehicle carried device operable for controlling the movement of the vehicle, roadside mechanism located at a control station on the roadside, an indication means for controlling the

operation of the device, a speed controller having a low speed contact, a vehicle carried mechanism cooperating with the roadside mechanism for automatically operating the said indication means, and means automatically conditioned for operation by the coaction of said roadside and vehicle carried mechanism for operating the device and for placing the same under the control of the low speed contact of the speed controller only during the period of cooperation between the roadside and vehicle carried mechanisms to permit the vehicle to move beyond the control station at a restricted speed.

18. In a vehicle control system, a vehicle carried device operable for controlling the movement of the vehicle, roadside ramps located at spaced controlling stations along the roadside, a speed controller, an indication means operable for producing a "proceed" operation in said device, for placing said device under the control of said speed controller and for producing a "stop" effect in said device, a vehicle carried shoe cooperating with said ramps and connected to produce the operations of the indication means; and means operable by the engagement of said shoe with a ramp when said "stop" effect is produced for placing the said device under the control of said speed controller at a low speed limit.

19. In a vehicle control system, a vehicle carried device for controlling the movement of the vehicle, roadside mechanism located at a control station on the roadside, vehicle carried mechanism cooperating with the roadside mechanism for automatically operating said device to produce a "stop" effect therein, manually controllable mechanism for modifying the "stop" operation of said device effective only during the period of non-coaction between said mechanisms and means for automatically modifying the said "stop" operation of said device during the period of coaction of said mechanisms.

20. In a vehicle control system, a vehicle carried device for controlling the movement of the vehicle, roadside mechanism located at a control station on the roadside, vehicle carried mechanism cooperating with the roadside mechanism for automatically operating said device to produce a speed restrictive effect therein, manually controllable mechanism for modifying the speed restrictive operation of said device effective only during the period of non-coaction between said mechanisms and means for automatically modifying the said speed restrictive operation of said device during the period of coaction of said mechanisms.

21. In a vehicle control system, a vehicle carried device for controlling the movement of the vehicle, roadside mechanism located at a control station on the roadside, vehicle carried mechanism cooperating with the roadside

mechanism for automatically operating said device to produce a "stop" effect therein, manually controllable mechanism for modifying the "stop" operation of said device during the period of non-coaction between said mechanisms, means for preventing said manually controllable mechanism from becoming effective during the period of coaction of said mechanisms, and means for automatically modifying the said "stop" operation of said device during the period of coaction of said mechanisms.

22. In a vehicle control system, a vehicle carried device for controlling the movement of the vehicle, roadside mechanism located at a control station on the roadside, vehicle carried mechanism cooperating with the roadside mechanism for automatically operating said device to produce a speed restrictive effect therein, manually controllable mechanism operably effective only when the vehicle is moving at or below a relatively low speed limit which is less restrictive than the said given restriction for operating the said device to impose a second relatively higher and fixed speed limit on the vehicle, said manually controllable mechanism being operably effective during the period of non-coaction between said vehicle carried and roadside mechanisms, and means for automatically modifying the said restrictive operation of said device during the period of coaction of said mechanisms.

23. In a vehicle control system, a vehicle carried device for controlling the movement of the vehicle, roadside mechanism located at a control station on the roadside, vehicle carried mechanism cooperating with the roadside mechanism for automatically operating said device to produce a "stop" effect therein, manually controllable mechanism operably effective only when the vehicle is moving at or below a relatively low speed limit for operating the said device to impose a second relatively higher and fixed speed limit on the vehicle, said manually controllable mechanism being so operably effective during the period of non-coaction between said vehicle carried and roadside mechanisms, and means for automatically modifying the "stop" operation of said device during the period of coaction of said mechanisms.

24. In a vehicle control system, a vehicle carried device for controlling the movement of the vehicle, roadside mechanism located at a control station on the roadside, vehicle carried mechanism cooperating with the roadside mechanism for automatically operating said device to produce a "stop" effect therein, manually controllable mechanism operably effective only when the vehicle is moving at or below a relatively low speed limit for operating the said device to impose a second relatively higher and fixed speed limit on the vehicle, said manually controllable mechanism being so operably effective during the period of non-coaction between said vehicle carried and roadside mechanisms, and means for automatically modifying the "stop" operation of said device during the period of coaction of said mechanisms.

limit on the vehicle, said manually controllable mechanism being so operably effective during the period of non-coaction between said vehicle carried and roadside mechanisms, and means for automatically modifying the "stop" operation of said device only during the period of coaction of said mechanisms to permit the vehicle to move under a speed restriction past said control station.

Signed at Niagara Falls, in the county of Niagara and State of New York, this 8th day of February A. D. 1924.

FRED M. ROSENZWEIG.
